METHOD OF AND MEANS FOR FOLDING
PAPER PRODUCTSIsidor Tornberg, Plainfield, N. J., assignor to
Wood Newspaper Machinery Corporation,
New York, N. Y., a corporation of Virginia

Application July 22, 1932, Serial No. 623,920

5 Claims. (Cl. 270—65)

This invention relates to the multiple folding of papers, for magazine and book work particularly, but is capable of use in newspaper printing and the like.

5 The principal object of the invention is to provide a method and means by which a fold, preferably the last fold, can be made with more facility than has been the case heretofore.

Other objects of the invention are to provide a 10 cutter on the folding couple for cutting through a plurality of thicknesses of the product being folded at a point at which the last and most difficult fold will come, to prevent the bunching of the paper at the corner between the last two 15 folds, and to provide an improved folded product having a notch at that corner instead of a bungling fold made up of a large number of sheets bent over each other in two directions at that corner.

20 Other objects and advantages of the invention will appear hereinafter.

Reference is to be had to the accompanying drawings, in which

25 Fig. 1 is a transverse sectional view of a folding couple, illustrating a preferred form of the mechanism of this invention, showing the rest of the folding mechanism diagrammatically in end elevation;

Fig. 2 is an elevation of the folding couple;

30 Fig. 3 is a view of the web which is to be folded, shown with the preparatory cut made;

Fig. 4 is a perspective view of the preliminary 35 folded sheet in the position in which it is being tucked into the folding rollers, and

Fig. 5 is a perspective view of the finished product.

In the production of magazines, books or papers in which the sheets are folded a number of times, it is customary to produce the first fold in the 40 direction of travel and the second fold by a rotary folding mechanism. In high speed printing presses this is as far as the product is folded. In magazine and book work an additional fold is required frequently in order to make a product 45 of a smaller size page and a larger number of pages from the same size sheet. The folds are made first in one direction and then in the other and with each fold the number of sheets to be folded the next time is doubled and consequently 50 the thickness of the papers being folded is doubled. Thus it becomes increasingly difficult to fold and produce a neat corner. In fact usually the corner at the end of the last fold and in the middle of the next to the last fold is made somewhat 55 bungling in character because it is difficult

to hold the paper and fold it in a neat form under the conditions.

This invention is designed to correct this difficulty by providing more freedom for the paper at that corner, thus allowing it to be folded easily 5 and naturally in a smooth and flat condition.

Referring to Fig. 1, the invention is shown as applied to an ordinary type of folding machine throughout a part of the course of the web. That is, the web W is fed down over the former 1 and shaped into the first fold by the form rolls 2, folding the web lengthwise. Thereafter it proceeds to the cutting and folding couple comprising the folding cylinder 3 and the cutting cylinder 4. Boxes 5 for rubbers are located on opposite sides 10 of the folding cylinder 3. These boxes carry full length cutting rubbers 7 for cooperation with the usual cutting blade 8 of the cutting cylinder to sever the continuous web into sheet lengths.

The folding cylinder is provided with short 20 boxes 9 for carrying short cutting rubbers 10, these being located at the longitudinal center of the folding cylinder and diametrically opposite each other and a quarter the way around the cylinder from the cutting boxes 5. On the cutting cylinder there is a short cutting knife 11, placed diametrically opposite the main cutting knife 8.

The folding cylinder is provided with the usual 25 rotary folding blade 13 folding the product into the folding rollers 14. From there the product is guided by guides 15 around the left hand folding roll and between it and an additional shaping roll 16. The product is shown as passing between the folding roller 14 in a vertical direction and now passes between a pair of rolls 14 and 16 in horizontal direction over a pair of transverse horizontal folding rolls 17. This product comes up against a stop 19 which leaves it in the proper 30 position to be pressed down between the rolls 17 by a vertically reciprocating folding blade 18. Although only one folding roll 17 is shown it is to be understood that a pair of them is located here in the same horizontal plane. The product 35 P is shown in Fig. 1 as supported on these rolls 17 and about to receive its final fold from the blade 18 which moves down between the rolls 17.

It will be obvious that the edge of the product 40 which comes up against the stop 19 is a folded edge and it has to be doubled over on itself which 45 bunches the paper at that point and makes it difficult to fold the product into the folding rolls 17.

It will be seen, however, that after the sheet 50 is cut by the blade 8 a slit S is cut into the sheet 55

transversely by the blade 11 at a point half way between the longitudinal edges of the sheet. This is shown as a single slit half way between the edges of the sheet, because that is the point at which this slit is desired for folding the product shown in Fig. 5 along the line X. The principle of the invention can be carried out in any way without departing from this invention by forming one or more slits where needed in the web prior 5 to folding to come at a folded edge or corner to facilitate the bending or folding of such edge or corner. This is a short slit preferably and does not weaken the paper and it comes of course in the middle of a margin of the folded product. 10 15 This slit comes at the center part of the edge which bears against the stop 19 and is located along that doubled edge and at the center thereof. Therefore, when the blade 18 comes down, this slit provides a weakness in the fold at that point 20 and prevents the necessity of stretching the outside layer of paper at that point over the inside layer which is folded within it. This greatly facilitates the final fold as it goes through the rollers 17. 25 30 I have shown this invention as applied to a particular type of folding machine but, of course, it can be applied to that type in which the first fold which is made over the former 1 could be made to double the number of sheets with a fold through the center of the former. In this case a slitter can be used as usual along the top center of the former. In other words this invention is applicable to folders for making the usual newspaper of tabloid size as well as to folders for making newspapers of the usual size shown in the drawings. 35 40 The slit S in the folded product facilitates the production of the last fold by freeing the paper where it is doubled the last time at the corner. This slit leaves the several thicknesses at the corner free from each other so that they will not bind and produce an undesirable thickness at that point.

Although I have illustrated and described only 45 one form of the invention I am aware of the fact

that modifications can be made therein by any person skilled in the art without departing from the scope of the invention as expressed in the claims. Therefore I do not wish to be limited in this respect otherwise than as set forth in the 5 claims, but what I do claim is:

1. The method of folding papers which consists in slitting a web at a point at which the end of the last folded edge is to be located to weaken the folded product at that point and 10 facilitate the production of the last fold.

2. The method of facilitating the folding of a sheet a plurality of times which consists in slitting a web prior to cutting it into sheets, at a point at which two folds are to cross each other. 15

3. The method of facilitating the folding of sheets which consists in providing a short slit centrally and transversely through each sheet along the line at which one fold is to be made and crossing the line at which another fold is to be 20 made.

4. The method of folding sheets which consists in cutting a double sheet transversely to form a short slit midway between its edges, folding the double sheet through the said slit along the slit, 25 and then folding the sheet transversely to the length of the slit and through the slit to free the last folded edges of the product from each other and facilitate its folding.

5. In a folding machine, the combination of a 30 former and forming rolls adapted to double a sheet longitudinally, a folding couple for receiving the doubled sheet, a pair of folding rolls cooperating with the folding couple and its blade to fold the doubled product transversely to the first fold, 35 a guide for guiding the twice folded product out of the folding rolls laterally, an additional pair of folding rolls having their axes at right angles to the last named pair in position for receiving the twice folded product, a blade for forcing the 40 product through the last named pair of folding rolls to fold the product longitudinally, and means for slitting the sheet before it is folded, at the end of the last folded edge of the product.

ISIDOR TORNBERG. 45
